BREAKDOWN FIREARM

William C. Roemer, New Haven, Conn., assignor
to Western Cartridge Company, New Haven,
Conn., a corporation of Delaware

Application October 4, 1939, Serial No. 297,852

4 Claims.

(Cl. 42—43)

The present invention relates to improvements in breakdown firearms, that is to say, firearms in which a butt-unit and a barrel-unit are movable (usually pivotally) with respect to each other, to separate the rear end of the cartridge-chamber of the barrel-unit from the standing-breech of the butt-unit, to permit the removal of just-fired cartridges and the insertion of fresh cartridges into the cartridge-chamber of the barrel-unit.

In order that a clearer understanding may be had of the present invention before a detailed description of one embodiment thereof is given, it may be first explained that it is customary in breakdown firearms to effect the cocking of the firing-member as the result of the so-called "breakdown" movement between the butt-unit and the barrel-unit. It is customary also to so proportion the parts that the firing-member is retarded sufficiently to be caught by the sear at a point prior to the point at which the two units of the firearm reach their full breakdown positions relative to each other. In other words, there is excess movement between the two said units after the firing-member has been retarded sufficiently to insure its being cocked. This excess movement, after the firing-member has been retarded into position to be cocked, is commonly referred to in the art as "over-cocking," since it retires the firing-member beyond the point required to effect its cocking in order to insure its being cocked. It is important to be noted, in this connection, that during this over-travel, or over-cocking, of the firing-member, the firing-spring is constantly exerting an effort to move the firing-member into engagement with the sear, and hence, since the cocking is effected by the breakdown movement of the firearm, the firing-spring (or springs) exerts a constant effort to close the two relatively-movable units of the firearm to a degree sufficient to bring the firing-member into engagement with the sear.

As will be more fully apparent hereinafter, the present invention is directed at overcoming the deleterious effects normally incident to over-cocking.

One of the objects of the present invention is to provide a superior breakdown firearm in which the effort of the firing-spring to effect the partial closing of the two units of the firearm, after the said firing-member has been retarded beyond its cocking position, is minimized or checkmated.

Another object of the present invention is to provide a superior breakdown firearm construction in which means is provided for automatically holding the firing-member in its over-

cocked position until such time as the two relatively-movable units of the firearm are moved toward their closed or normal positions.

A further object of the present invention is to provide a superior breakdown firearm construction in which a releasable retaining- or latching-bolt is employed to hold the firing-member in its over-cocked position, and which bolt is automatically released by the bringing of the two relatively-movable units of the firearm into their normal or closed positions relatively to each other.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view in side elevation of a breakdown shotgun embodying the present invention;

Fig. 2 is a top or plan view thereof;

Fig. 3 is a broken view mainly in vertical central-longitudinal section and partly in side elevation of the portions of the firearm adjacent the forward end of the butt-unit and the rear end of the barrel-unit, the two units being shown in their normal or closed positions;

Fig. 4 is a view similar to Fig. 3 but showing the parts in the positions which they assume when the firearm is broken down sufficiently to effect the cocking of the firing-member but prior to the full breakdown of the firearm;

Fig. 5 is a similar view but showing the parts in the positions which they assume when the firearm is in its full breakdown position and the firing-member is latched in its over-cocked position;

Fig. 6 is a broken view in horizontal section taken on the line 6—6 of Fig. 3;

Fig. 7 is a vertical transverse sectional view taken on the line 7—7 of Fig. 3;

Fig. 8 is a similar view taken on the line 8—8 of Fig. 3;

Fig. 9 is a perspective view of the two cocking-levers;

Fig. 10 is a perspective view of one of the two sears;

Fig. 11 is a perspective view of the right-hand firing-member or plunger; and

Fig. 12 is a perspective view of the locking-bolt.

The particular breakdown firearm herein chosen for the illustration of the present inven-

tion is in the form of a double-barreled shotgun which includes a butt-unit generally designated by the reference character 20 and a barrel-unit generally designated by the reference character 21. The butt-unit 20 just referred to, includes in the main a buttstock 22 attached at its forward end to the rear end of a frame 23. The barrel-unit 21 includes two barrels, namely, a right-hand barrel 25 and a left-hand barrel 26, which are secured together in any suitable manner substantially throughout their length, and which are jointly provided at their rear ends with a depending barrel-lug 27 which is pivoted in any approved manner to a pivot-pin 28 extending transversely of the forward portion of the frame 23 in a manner more or less conventional in breakdown firearms.

As thus constructed and arranged, the butt-unit 20 and the barrel-unit 21 may be pivoted with respect to each other about the pivot-pin 28 to permit the removal of just-fired cartridges and the insertion of fresh cartridges, as is indicated particularly well by broken lines in Fig. 1.

Removably secured to the under face of the barrel-unit 21 and normally forming a part thereof, is a forestock-unit 29 requiring no detailed description herein other than to state that it includes at its rear end a forestock-shoe 30 and a forwardly-extending forestock proper 31 preferably formed of wood or other heat-insulating material. As is more or less usual in breakdown firearms, the forestock-shoe 30 just referred to is formed in its rear face with a cylindrically-contoured surface 32 normally bearing against the similarly-contoured forward edge 33 of the frame 23.

The barrel-lug 27 before referred to, is formed with a downwardly-opening central-longitudinal groove 34 which, in addition to other features, accommodates the respective forward ends of a right-hand cocking-lever 35 and a left-hand cocking-lever 36, both of which are of substantially L-shaped form and located alongside of each other, as is especially well shown in Fig. 9.

Both the right-hand cocking-lever 35 and the left-hand cocking-lever 36 are mounted for rocking movement on a pivot-pin 37. The said pivot-pin 37 is mounted at its respective opposite ends (Fig. 7) in the opposite side walls of a longitudinally-grooved mounting-member 38 secured by brazing, or otherwise, to the upper face of a trigger-plate 39 forming a unitary part of the frame 23 and carrying a loop-like trigger-guard 40.

The forward portion of the mounting-member 38 and the respective forward portions of the cocking-levers 35 and 36 project forwardly through a suitable opening provided in the lower portion of the standing-breech 41 of the frame 23. Rearwardly of the said standing-breech 41 is mounted the rotary stem 42 rigidly secured to and depending from the forward end of a so-called "top-lever" 43 located mainly upon the upper face of the frame 23 and turnable about the axis of the stem 42 as the center from the position in which it is shown by full lines in Fig. 2, to the position in which it is shown by broken lines in the same figure.

On its left side, the stem 42 of the top-lever 43 is provided with a coupling-notch 44 (Fig. 6) into which fits a coupling-pin 45 upstanding from a plate-like reciprocating locking-bolt 46 adjacent the left edge of the latter, so that a turning movement of the stem 42 will effect the rearward retraction of the locking-bolt 46. Adjacent its rear end, the said locking-bolt 46 is formed

with a central-longitudinal clearance-groove 47 through which downwardly extends a bearing-pin 48 depending from the stem 42 and rotating in a suitable bearing 49 forming a feature of the frame 23 and serving to stabilize the lower end of the said rotary stem 42.

The forward edge 50 of the reciprocating locking-bolt 46 is slightly forwardly-and-downwardly inclined for the purpose as will hereinafter appear, and is projectable forwardly of the standing-breech 41 of the frame 23 for entry into a rearwardly-opening locking-notch 27a in the barrel-lug 27. The said forward edge 50 is also engaged by the beveled lower rear corner 51 of the barrel-lug 27 to effect the retirement of the said locking-bolt 46, as will hereinafter appear.

In its under face, mainly adjacent its forward end, the locking-bolt 46 is provided with a central-longitudinal groove 52 to accommodate on occasion the substantially-horizontal lower portions of the respective cocking-levers 35 and 36 and to provide a relatively-slender latching-abutment 53 which is upon occasion "hooked under" so to speak, two latching-noses 54—54, one of which is formed upon each of the cocking-levers 35 and 36.

As will be seen particularly well by reference to Fig. 9, the right-hand cocking-lever 36 is formed with a lateral actuating-bar 55 which extends across the front face of the upstanding portion of the left-hand cocking-lever 35 for the purpose as will presently appear. The rear face of the rotary stem 42 of the top-lever 43 is flattened, as will be clear by reference to Fig. 6 in particular, so as to provide a retracting-cam 56 on the left rear face of the said stem. The said retracting-cam 56 engages with the forward face of the actuating-bar 55 at the upper end of the cocking-lever 35, when the said rotary stem 42 is turned in a counterclockwise direction by the manual manipulation of the top lever 43. This movement serves to rock both of the cocking-levers 35 and 36 for the purpose as will hereinafter appear.

The rear face of the upper portion of the cocking-lever 35 is adapted to engage with the forward face of an actuating-finger 57 projecting laterally inwardly from a firing-member or plunger 58 designed to discharge a cartridge in the right-hand barrel 26 of the barrel-unit 21. The firing-member 58 includes a forwardly-extending firing-point 59 projectable through a suitable passage through the standing-breech 41 in substantial axial alignment with the center of the right-hand barrel 25. The said firing-member 58 is also provided with a rearwardly-extending shank 60 which is guided at its rear end in the adjacent rear arm of an inverted U-shaped yoke 61, as is shown particularly well in Figs. 3 and 6. Encircling the shank 60 of the firing-member 58 is a helical firing-spring 62 which thrusts at its rear end against the yoke 61 and at its forward end against the portion of the firing-member 58 from which the shank 60 projects, so as to exert a constant effort to move the said firing-member forwardly.

On its under face, the firing-member 58 is formed with a forwardly-facing cocking-abutment 63 which is adapted to be engaged by the rear face of a cocking-nose 64 formed at the forward end of a pivotal sear 65. The said sear 65 is mounted for pivotal movement upon a pivot-pin 66 carried in the rear portion of the mounting-member 38 before referred to. The rear end of the sear 65 is adapted to be engaged and lifted

by a lifting-lug 67 formed upon the upper portion of a trigger 68 mounted for pivotal movement upon a trigger-pin 69 (Fig. 3) carried by the trigger-plate 39 before referred to.

The left-hand cocking-lever 36 is adapted to perform the same functions as those described above for the right-hand cocking-lever 35, but upon a separate mechanism which is a substantial duplicate of the mechanism above described and not requiring detailed description herein other than that on occasion where required, the parts will bear the same reference characters as those applied to the elements associated with the right-hand cocking-lever 35, plus the additional designation "a."

Returning now to the top-lever 43 and its rotary stem 42, the said top-lever is yieldingly retained in its central position, as indicated by full lines in Fig. 2, by means of a spring-pressed plunger 70 normally thrusting against a rearwardly-facing surface 71 extending substantially diametrically across the stem 42 closely beneath the top-lever 43. The said plunger 70 bears at its rear end in the forward portion of the inverted U-shaped yoke 66 secured to the under face of the top wall of the frame 23. The said plunger 70 is urged forwardly by a helical spring 72 which encircles its rear portion, as is particularly well shown in Fig. 3.

Slidably mounted in the downwardly-opening central-longitudinal groove 34 in the barrel-lug 27 is a bar-like cocking-shoe 73 having its rear end normally underlying the forward under faces of the respective cocking-levers 35 and 36. The cocking-shoe 73 is held in its rear or operating position by a shoe-retainer 74 pivotally mounted by means of a pivot-pin 75 to the forestock-shoe 30. When the forestock-unit 29 is removed from the barrel-unit 21, the cocking-shoe 73 may slide forwardly out from the cocking-levers 35 and 36, to thus permit the unhindered removal or detachment of the said barrel-unit 21 from the butt-unit 20.

For purposes of making clear the operation of the embodiment of the present invention shown in the accompanying drawings and described above, let it be assumed that the parts are in the positions in which they are indicated in Fig. 3, which represents the conditions prevailing immediately following the discharge of the firearm.

The first operation now required is to swing the rear end of the top lever 43 from left to right, from the position in which it is shown by full lines in Fig. 2 to the position in which it is shown by broken lines in the same figure. This movement will turn the stem 42 against the tension of the spring 72 and will retract the forward portion of the reciprocating locking-bolt 46 out of the locking-notch 21a of the barrel-lug 27, to thereby permit the barrel-unit 21 to be swung about the pivot-pin 28 as a center. The initial swinging movement of the stem 42 of the top lever 43 will also cause the actuating-cam 56 of the said stem to engage with and force the actuating-bar 55 of the right-hand cocking-lever 35 rearwardly. Owing to the overlapping relationship of the actuating-bar 55 with respect to the forward face of the upper end of the left-hand cocking-lever 36, both levers will be simultaneously tilted in a counterclockwise direction to a degree sufficient to retire the firing-point 59 of the firing-member 58 and the firing-point 59a of the firing-member 58a rearwardly of the front face of the standing-breech 41. This particular feature is not by itself claimed herein, but forms the subject-matter

of a separate application filed by me October 6, 1939, Serial No. 298,166.

After the locking-bolt 46 has been retired as above described and the barrel-unit 21 swung into the position in which it is indicated in Fig. 4, the cocking-shoe 73 will have lifted the forward end of the cocking-lever 35 sufficiently to have caused the said cocking-lever to retire the firing-member 58 into the position in which it is shown in Fig. 4, to thereby move its cocking-abutment 63 to the rear of the sear-nose 64. The barrel-unit 21 has not as yet, however, been swung sufficiently to permit the extraction of a fired shell from the rear end of the barrel-unit.

15 The continued swinging movement of the barrel-unit 21 from the position shown in Fig. 4 into the position in which it is shown in Fig. 5 will, through the intermediary of the cocking-shoe 73, further tilt the cocking-lever 35 to raise its 20 latching-nose 54 above the latching-abutment 53 of the retired locking-bolt 46 and also to further retire the firing-member 58 against the opposition of the firing-spring 62. In this manner, the cocking-abutment 63 of the firing-member 58 will be moved rearwardly of the cocking-nose 64 of the sear 65. Manual pressure upon the top lever 43 should now be relaxed.

Were it not for provision to the contrary, the firing-spring 62 would, acting through the cocking-lever 35, now serve to return the barrel-unit 21 to the position in which it is shown in Fig. 4, since the said firing-spring would be free to swing the cocking-lever 35 a distance sufficient to bring the cocking-abutment 63 of the firing-member 58 into engagement with the cocking-nose 64 of the sear 65.

As soon, however, as the barrel-unit 21 reaches the position in which it is shown in Fig. 5, the locking-nose 54 of the cocking-lever 35 will have been shifted above the latching-abutment 53 of the locking-bolt 46, and the said locking-bolt (finger pressure upon the top lever 43 having by this time been released) will snap forwardly under the urge of the spring 72 and releasably latch the firing-member 58 in the position in which it is shown in Fig. 5. In this manner, the firing-spring 62 is prevented from exerting an effort to shift the barrel-unit 21 from the position in which it is shown in Fig. 5 back to the position in which it is shown in Fig. 4.

After the parts reach the positions in which they are shown in Fig. 5 and the fired cartridge has been extracted, the barrel-unit 21 may be manually returned to the position in which it is shown in Figs. 1, 2 and 3. As the barrel-unit approaches its closed or breeched position, the lower rear corner 51 of the barrel-lug 27 will engage with the forward edge 50 of the locking-bolt 46 and retire the said locking-bolt rearwardly. As soon as the said locking-bolt has been retired sufficiently to clear its latching-abutment 53 from the latching-nose 54 of the cocking-lever 35, the said cocking-lever will be swung in a clockwise direction by the firing-spring 62 and the locking-bolt 46 will be freed to have its forward edge 50 entered into the locking-notch 21a in the barrel-lug 27 as soon as the said locking-notch is brought into registration therewith by the closing movement of the barrel-unit 21.

The same effect as has been above described, in connection with the right-hand cocking-lever 35 and its associated features, will occur to the left-hand cocking-lever 36 and its associated

features simultaneously with the action above described. Thus, no detail description is required of the operation of the features associated with the left-hand barrel 26 of the barrel-unit 21.

By the construction and arrangement of parts above described and shown in the accompanying drawings, the annoying tendency of the barrel-unit to swing partly into its closed position, under the urge of one or more of the firing-springs, is effectively avoided, and the firearm is made much more convenient to load and unload than would otherwise be the case.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A breakdown firearm including in combination: a butt-unit; a barrel-unit pivoted to the said butt-unit for movement into both a closed and a breakdown position with respect thereto; a releasable locking-bolt for holding the two said units in their normal or closed positions with respect to each other; a firing-member retractable into a cocked position and into an over-cocked position; a firing-spring urging the said firing-member into its firing-position; a sear for releasably holding the said firing-member in its cocked position; cocking-means operable by the breakdown movement of the two said units with respect to each other to retire the said firing-member into its over-cocked position and constructed and arranged to be releasably engaged by the aforesaid locking-bolt to releasably hold the said firing-member in its over-cocked position.

2. A breakdown firearm including in combination: a butt-unit; a barrel-unit pivoted to the said butt-unit for movement into both a closed and a breakdown position with respect thereto; a releasable spring-pressed locking-bolt for holding the two said units in their normal or closed positions with respect to each other; a firing-member retractable into a cocked position and into an over-cocked position; a firing-spring urging the said firing-member into its firing-position; a sear for releasably holding the said firing-member in its cocked position; cocking-means operable by the breakdown movement of the two said units with respect to each other to retire the said firing-member into its over-cocked position and constructed and arranged to be releasably engaged by the aforesaid locking-bolt to releasably hold the said firing-member in its over-cocked position; and releasing-means actuated by the closing movement of the two said units to retire the said locking-bolt and release the said

cocking-means and hence release the said firing-member for movement into cocking-engagement with the said sear.

3. A breakdown firearm including in combination: a butt-unit; a barrel-unit pivoted to the said butt-unit for movement into both a closed and a breakdown position with respect thereto; a releasable spring-pressed locking-bolt for holding the two said units in their normal or closed positions with respect to each other; a firing-member retractable into a cocked position and into an over-cocked position; a firing-spring urging the said firing-member into its firing-position; a sear for releasably holding the said firing-member in its cocked position; and a cocking-lever pivoted to the said butt-unit and having a first arm engageable with the said firing-member and a second arm engageable with a portion of the said barrel-unit for being actuated thereby to rock the said cocking-lever into position to retire the said firing-member into its over-cocked position when the said barrel-unit is swung into its breakdown position with respect to the said butt-unit, the said second arm of the said cocking-lever having a portion positioned to be releasably engaged by the said locking-bolt to releasably hold the cocking-lever in position to hold the said firing-member in its over-cocked position.

4. A breakdown firearm including in combination: a butt-unit; a barrel-unit pivoted to the said butt-unit for movement into both a closed and a breakdown position with respect thereto; a releasable spring-pressed locking-bolt for holding the two said units in their normal or closed positions with respect to each other; a firing-member retractable into a cocked position and into an over-cocked position; a firing-spring urging the said firing-member into its firing-position; a sear for releasably holding the said firing-member in its cocked position; a cocking-lever pivoted to the said butt-unit and having a first arm engageable with the said firing-member and a second arm engageable with a portion of the said barrel-unit for being actuated thereby to rock the said cocking-lever into position to retire the said firing-member into its over-cocked position when the said barrel-unit is swung into its breakdown position with respect to the said butt-unit, the said second arm of the said cocking-lever having a portion positioned to be releasably engaged by the said locking-bolt to releasably hold the cocking-lever in position to hold the said firing-member in its over-cocked position; and a tripping-abutment carried by the said barrel-unit and engaging with the said locking-bolt when the barrel-unit is swung into its closed position, to retire the said locking-bolt and release the said cocking-lever and hence release the said firing-member for cocking-engagement with the said sear.

WILLIAM C. ROEMER.
